UNITED STATES PATENT OFFICE.

HENRY WEHMILLER, OF CLARINDA, IOWA.

DITCHING-MACHINE.

SPECIFICATION forming part of Letters Patent No. 776,576, dated December 6, 1904.

Application filed May 27, 1904. Serial No. 210,124. (No model.)

To all whom it may concern:

Be it known that I, HENRY WEHMILLER, a citizen of the United States, residing at Clarinda, in the county of Page and State of Iowa, 5 have invented a new and useful Ditching-Machine, of which the following is a specification.

This invention relates to ditching-machines, and has for its object to produce a device of this character of improved construction and 10 increased efficiency.

With these and other objects in view, which will appear as the nature of the invention is better understood, the same consists in certain novel features of construction, as herein- 15 after fully described and claimed.

In the accompanying drawings, forming a part of this specification, and in which corresponding parts are denoted by like designating characters, is illustrated the preferred 20 form of the embodiment of the invention capable of carrying the same into practical operation, it being understood that the invention is not necessarily limited thereto, as various changes in the shape, proportions, and 25 general assemblage of the parts may be resorted to without departing from the principle of the invention or sacrificing any of its advantages, and the right is therefore reserved of making all the changes and modifications 30 which fairly fall within the scope of the invention and the claims made therefor.

In the drawings thus employed, Figure 1 is a side elevation, partially in section, and Fig. 2 is a plan view, also partially in section, 35 of the improved apparatus. Fig. 3 is a sectional detail view of a part of the apparatus.

The improved apparatus is supported upon a bed-frame 10 of suitable size and strength and mounted upon carrying-wheels 11 12 and 40 also carrying a suitable motor (indicated at 13) for transmitting motion to the cutting mechanism and which may also be employed for transmitting motion to the traction-wheels when such means for moving the machine is 45 employed.

Any suitable means may be employed for drawing the frame and its attachments over the ground; but as these form no part of the present invention they are not illustrated.

Attached rigidly to the side members of the

frame 10 are oppositely-disposed brackets 14 15, having segmental slots or elongated bearings, one of which is shown at 16, in which the ends of a shaft 17 are rotatively mounted and suitably supported from end movement, 55 as by collars 18 19. The brackets 14 15 are also provided, respectively, with segmental gear-racks, one of which is shown at 20, with which pinions 22 23, rigidly attached to the shaft 17, engage, the object and operation to 60 be hereinafter explained.

Mounted for free rotation upon the shaft 17 is a wheel (represented as a whole at 24) having a plurality of spaced peripheral pockets or receivers 25 open at the sides and provided 65 with tangentially-disposed cutting members 26 for cutting the material and guiding it into the pockets as the wheel is rotated. The open sides of the pockets 25 are provided with doors or closures 27 28, hinged, respectively, at the 70 intake ends of the pockets, as at 29 30, so that as the wheel is rotated the doors will open by gravity when the wheel reaches a certain pre-determined position to discharge the contents of the pockets, as hereinafter explained. At- 75 tached to or forming a part of the wheel is a gear-rim 31, concentric to the shaft 17.

Mounted for rotation transversely of the frame 10 is a shaft 32, and pivoted by one end at 33 to this shaft is a radius-frame formed of 80 two spaced side members 34 35, passing each side of the wheel 24 and pivoted by their free ends to the shaft 17, as at 36 37.

Connected to the shaft 17 and partaking of its motion is a worm-gear 38, and extending 85 from the radius member 34 are spaced standards 39 40 and carrying a shaft 41, having at one end an operating-crank 42 and at the other end a worm-pinion 54 for engaging the worm-gear 38.

Mounted for rotation upon the radius member, as by bearings 43 44, is a counter-shaft 45, having at one end a pinion 46 for engaging the gear-rim 31 and at the other end a bevel-pinion 47, engaged by a similar bevel- 90 pinion 48 on the shaft 32. The shaft 32 is connected to be operated, as by a chain 49 leading from the motor 13 to a chain-wheel 50 on the shaft.

Guard members 51 52 will preferably be 100

connected to the radius members and curved concentrically to the wheel 24 to extend in close proximity to the compartment-closures 27 28 to maintain them in closed position until they arrive at the point where they are to be discharged.

In operating the machine the cutting-wheel 24 is elevated above the ground by rotating the worm-pinion 54 backwardly and the machine drawn to the starting-point of the ditch and motion imparted to the cutting-wheel and the same lowered gradually by rotating the worm-pinion forwardly, the wheel cutting as it moves downwardly and forcing the excavated earth into the pockets 25. The closures 27 28 are held closed by the sides of the ditch while the same are beneath the ground and are held closed by the guard members 51 52 after they pass above the ground and until they pass the upper ends of the same, when the closures will fall open by gravity and by hanging at an outward and downward incline form chutes to carry the earth falling from the compartments away from the wheel and discharge it along the banks outside the framework 10. As the cutting-wheel continues to revolve the open closure striking the side members of the frame 10 are closed thereby in position for the next action. Thus the action of the cutting-wheel is entirely automatic and cuts a uniform-sized ditch and is of any desired depth within the range of the guide members 14 15.

The machine can be constructed of any required size and of any required strength or material, is very simple in construction, and will operate efficiently for the purposes described.

Having thus described the invention, what is claimed is—

1. In a ditching-machine, a supporting-frame for movement over the ground and having oppositely-disposed segmental guide members provided with segmental gear-racks, a shaft mounted for rotation in said guide members and having gear-pinions for engaging the racks therein, a wheel mounted for rotation upon said shaft and having a plurality of spaced pockets in its periphery and with tangentially-disposed cutting members for guiding the material into said pockets, means for discharging the material laterally from the pockets, a gear-wheel carried by said cutting-wheel, a radius-frame pivoted by the ends respectively to said frame and to said shaft, a pinion carried by said radius-frame for engaging said gear-wheel, means for rotating said gear-pinions for operating said cutting-wheel, and means for rotating said shaft to adjust said cutting-wheel vertically.

2. In a ditching-machine, a supporting-frame for movement over the ground and having oppositely-disposed segmental guide members provided with segmental gear-racks, a shaft mounted for rotation in said guide mem-

bers and having gear-pinions for engaging the racks therein, a wheel mounted for rotation upon said shaft and having a plurality of spaced pockets in its periphery and with tangentially-disposed cutting members for guiding the material into said pockets, means for discharging the material laterally from the pockets, means carried by said frame for rotating said wheel, and means for independently rotating said shaft to adjust said wheel vertically relative to said frame.

3. In a ditching-machine, a wheel for rotative movement toward its work and formed with a plurality of spaced pockets in its periphery and with tangentially-disposed cutting members for guiding the material into said pockets, said pockets being open at the sides and having closing-valves swinging from the intake ends of the pockets, whereby the valves will open by gravity at a certain predetermined point in the rotation of the wheel.

4. In a ditching-machine, a wheel for rotative movement toward its work and formed with a plurality of spaced pockets in its periphery and with tangentially-disposed cutting members for guiding the material into said pockets, said pockets being open at the sides and having closing-valves swinging from the intake ends of the pockets, and stop members for engaging said valves to hold them closed until they reach a certain predetermined point in the rotation of the wheel.

5. In a ditching-machine, a supporting-frame for movement over the ground and having oppositely-disposed segmental guide members provided with segmental gear-racks, a shaft mounted for rotation in said guide members and having gear-pinions for engaging the racks therein, a wheel mounted for rotation upon said shaft and having a plurality of spaced pockets in its periphery and tangentially-disposed cutting members for guiding the material into said pockets, means for discharging the material laterally from the pockets, a shaft mounted for rotation upon said frame, a radius-frame pivoted by one end to said frame-supported shaft and by the other end to said wheel-supporting shaft, a gear-wheel carried by said cutting-wheel, a counter-shaft carried for rotation upon said radius-frame and having at one end a gear-pinion for engagement with said cutting-wheel gear and at the other end having a bevel-pinion engaging a bevel-pinion on said frame-supported shaft, means for rotating the frame-supported shaft for transmitting motion to said cutting-wheel, and means for rotating said cutting-wheel-supporting shaft for vertically adjusting the cutting-wheel.

6. In a ditching-machine, a supporting-frame for movement over the ground and having oppositely-disposed segmental guide members provided with segmental gear-racks, a shaft mounted for rotation in said guide members and having gear-pinions for engag-

ing the racks therein, a wheel mounted for rotation upon said shaft and having a plurality of spaced pockets in its periphery and with tangentially-disposed cutting members 5 for guiding the material into said pockets, means for discharging the material laterally from the pockets, a shaft mounted for rotation upon said frame, a radius-frame pivoted by one end to said frame-supported shaft and 10 by the other end to said wheel-supporting shaft, a gear-wheel carried by said cutting-wheel, a counter-shaft carried for rotation upon said radius-frame and having at one end a gear-pinion for engagement with said cutting-wheel gear and at the other end having 15 a bevel-pinion engaging a bevel-pinion on said frame-supported shaft, means for rotating

the frame-supported shaft for transmitting motion to said cutting-wheel, a worm-gear carried by said cutting-wheel shaft, spaced 20 standards carried by said radius-frame, and a shaft mounted for rotation in said standards and having at one end an operating-crank and at the other end a worm-pinion for engaging said worm-gear whereby said cutting-wheel 25 shaft may be rotated for adjusting the same and locked at any desired point of elevation.

In testimony that I claim the foregoing as my own I have hereto affixed my signature in the presence of two witnesses.

HENRY WEHMILLER.
